CLAIM

The ornamental design for a wearable coaching device with buttons, as shown and described.

DESCRIPTION

FIG. 1 is a perspective view of the wearable coaching device with buttons of the present invention.

FIG. 2 shows the wearable coaching device with buttons of FIG. 1, with the wearable coaching device with buttons depicted in a top view;

FIG. 3 shows the wearable coaching device with buttons of FIG. 1, with the wearable coaching device with buttons depicted in a bottom view;

FIG. 4 shows the wearable coaching device with buttons of FIG. 1, with the wearable coaching device with buttons depicted in a left side view;

FIG. 5 shows the wearable coaching device with buttons of FIG. 1, with the wearable coaching device with buttons depicted in a right side view;

FIG. 6 shows the wearable coaching device with buttons of FIG. 1, with the wearable coaching device with buttons depicted in a back side view; and,

FIG. 7 shows the wearable coaching device with buttons of FIG. 1, with the wearable coaching device with buttons depicted in a front side view.
